UNITED STATES PATENT OFFICE.

NEKIFOR BOLOGA, OF CLEVELAND, OHIO.

STILL.

1,379,520.

Specification of Letters Patent. Patented May 24, 1921.

Application filed January 16, 1920. Serial No. 351,807.

To all whom it may concern:

Be it known that I, NEKIFOR BOLOGA, citizen of the United States of America, residing at Cleveland, in the county of Cuyahoga and State of Ohio, have invented new and useful Improvements in Stills, of which the following is a specification.

The object of my present sole invention is the provision of a simple, efficient, easily operated and easily cleaned still, designed more especially, though not necessarily, for the production of fruit brandy and the like.

This application is a substitute for applicant's abandoned application Serial No. 15 182,164, filed July 23, 1917.

To the attainment of the foregoing, the invention consists in the improvement as hereinafter described and definitely claimed.

In the accompanying drawings:

20 Figure 1 is a diametrical section of the still constituting the best practical embodiment of my invention of which I am cognizant.

Fig. 2 is a plan view of the same.

25 Fig. 3 is a plan view of the foraminous receptacle comprised in the still.

Fig. 4 is a detail view showing one of the loops or eyes in the said foraminous receptacle.

30 Fig. 5 is a detail view of the gravitational valve complementary to the central discharge orifice of the foraminous receptacle.

Similar numerals of reference designate corresponding parts in all of the views of 35 the drawings.

Among other elements my novel still includes a casing body 1 having an exterior and apertured flange 2 at its upper end, and also having a diametrically disposed channel 40 3 in its bottom; said channel 3 being in communication with a drainage pipe 4 that is provided with a faucet 5.

The said casing body 1 is equipped with a cap 6 having an apertured flange 7, and 45 also having a central flanged opening 8 and a bar 9 bridging said opening and provided with a central aperture 10. An apertured annulus 11 surrounds the body 1 below the flange 2 thereof, and is connected with the 50 flange 7 of the cap 6 through the medium of bolts 12. It will also be understood that an upper annulus 13 is superimposed upon the flange of the cap 6 and receives the said bolts 12 so as to strengthen the connection 55 of the cap 6 to the casing body 1.

Removably arranged in the casing body 1,

and maintained in spaced relation thereto, as indicated by 14 in Fig. 1, is a foraminous receptacle 15 having a central discharge aperture 16, and also having an outwardly 60 extending apertured flange 17, the latter being preferably of sheet-metal and fixedly joined at its inner edge to the upper edge of the receptacle 15. The said foraminous receptacle is provided interiorly with four 65 (more or less) loops or eyes 18, and has detachably secured on its bottom an upstanding bridge loop 19 in which is a central aperture 20. The detachable connection of the bridge loop 19 to the bottom of the receptacle 15 is preferably effected by turn-buttons 21, as illustrated. Detachably connected to the side wall of the receptacle 15 at diametrically opposite points, and preferably through the medium of turn-buttons 22, 70 are the pendent end portions 23 of a detachable cross-bar 24 in which is a central aperture 25. A gravitational valve 26 is employed to control the aperture 16 of the receptacle 15. Said valve has a stem 27 that 75 extends through the apertures of the bridge loop 19 and the cross-bar 24. The said stem 27 is provided adjacent to its upper end with an aperture 28 in which a rod, not shown, may be inserted by the operator for the 80 convenient raising of the valve 26 after the cap 6 is removed from the body 1. Manifestly when the bridge loop 19 and the cross-bar 24 are disconnected from the receptacle 15, the 85 said elements 19 and 24, together with the valve 26, may be removed from the foraminous receptacle 15 to facilitate the thorough cleansing thereof.

The flange 17 of the receptacle 15 is interposed between the flanges of the casing body 1 and the cap 6, and gaskets are arranged above and below said flange 17 so as to render the connection between the casing and the receptacle 15 steam-tight.

In addition to the elements thus far al- 100 luded to, my novel still comprises a removable dome 30 having a reduced lower portion 31 that is socketed and held by frictional contact in the collar flange 7 of the cap 6. The said dome is provided with 105 two, more or less, outlet pipes 32 for vapor, and is provided at its upper side with two handles 33, so as to permit of its being independently lifted off the cap 6.

In the practical operation of my novel 110 still, the cap 6 is removed for the placing of the fruit in the foraminous receptacle 15,

and the cap is then replaced and the casing body 1 subjected to the proper degree of heat, in any approved manner. Incidental to the use of the still, it will be observed 5 that the foraminous receptacle 15 effectively prevents the heavy material, such as apples and peaches, adhering to the inner side of the body 1, with the result that injury to the material is precluded, and the likelihood of 10 a bad taste being imparted to the brandy is done away with. On the other hand only the liquefied substance will pass through the foraminations of the receptacle, and when the liquid is put in a state of ebullition, the 15 contents of both casing body 1 and receptacle 15 will be kept in motion, with the result that the liability of burning is reduced to a minimum.

When the cap 6 or the dome 30 is removed, 20 and the valve is lifted through the medium of a rod placed in the aperture of the stem thereof, the contents of the foraminous receptacle may be let into the channel 3 in the bottom of the body 1 to be drained from 25 the still.

During the operation of the still, the pipes

32 may be and preferably are cooled in the ordinary manner, or in any other approved manner.

Having described my invention, what I 30 claim and desire to secure by Letters-Patent is:

A still comprising a casing body having a drainage channel in its bottom, a valved drainage pipe carried by the body and communicating with said channel, a foraminous receptacle supported in the casing body in spaced relation thereto and having a discharge opening in its bottom, an apertured bridge loop and an apertured cross-bar 35 detachably secured in the foraminous receptacle, a gravitational valve complementary to the discharge aperture in the foraminous receptacle and having a stem guided in the apertures of the bridge loop and cross-bar, 40 loops or eyes secured to the foraminous receptacle and arranged within the same, and means closing the casing body and inclosing the receptacle therein and having vent 45 means. 50

In testimony whereof I affix my signature.

NEKIFOR BOLOGA.
